(57) **CLAIM**

The ornamental design for a differential reinforcement bracket, as shown and described.

DESCRIPTION

FIG. 1 is a front, top perspective view of a differential reinforcement bracket, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof;

FIG. 7 is a left-side elevational view thereof;

FIG. 8 is a cross-sectional view thereof, taken along line 8-8 of FIG. 4;

FIG. 9 is a rear, bottom perspective view thereof, illustrated with a cushioning element of the design removed for clarity of illustration; and,

FIG. 10 is a rear, top perspective view of FIG. 9.

The broken lines showing a differential in FIG. 1 depict environmental matter and form no part of the claimed design. The remaining broken lines showing a logo of the reinforcement bracket form no part of the claimed design.
